S. P. WILBUR

ENGINE REGULATOR

Filed June 14, 1920

UNITED STATES PATENT OFFICE.

SAMUEL P. WILBUR, OF TOLEDO, OHIO, ASSIGNOR, BY MESNE ASSIGNMENTS, TO THE ELECTRIC AUTO-LITE COMPANY, OF TOLEDO, OHIO, A CORPORATION OF OHIO.

ENGINE REGULATOR.

Application filed June 14, 1920. Serial No. 388,840.

This invention relates to electric power plants in which an internal combustion engine, constituting the prime mover, drives a dynamo-electric machine which charges a storage battery for supplying electric energy to lamps, motors, etc. In plants of this character the battery normally carries the load and, in the case of the non-automatic type, is charged when necessary by the engine driven generator. The engine and generator, under normal conditions, run at a substantially constant speed and charge the battery at a predetermined rate. When translating devices, such as motors, are being operated from the battery it is often found expedient to run the engine to assist the battery in carrying the load, in which case part of the generated current may be taken by the battery and part taken by the load. Despite the fact that the engine and generator may be in operation, an exceptionally heavy load on the system may require even more power than the generator and battery can supply. Were a fixed higher charging rate to be provided to take care of such a condition the battery might be injured by the excessive charging rate under a light or no-load condition. It is an object of my invention, therefore, to provide for charging the battery at the normal rate under no-load or light-load conditions and to increase the power of the engine to supply a materially greater amount of electric power to the load and battery circuits jointly when an excessively heavy load is thrown on. In carrying out my invention I provide a valve in the venturi at the intake side of the engine which valve normally partially restricts the intake of air and fuel to the engine. The valve forms a part or extension of the plunger or armature of an electromagnet, the coil of which is connected in series with the load circuit and is operated to permit a substantially free flow of air and fuel to the engine when the load current reaches a predetermined value.

Further objects of this invention relate to economies of manufacture and details of construction as will hereinafter appear from the detailed description to follow. I accomplish the objects of my invention in one instance by the devices and means described in the following specification, but it is evident that the same may be varied widely without departing from the scope of the in-

vention as pointed out in the appended claims. A structure constituting one embodiment of my invention, which may be preferred, is illustrated in the accompanying drawings forming a part hereof, in which:

Figure I is a vertical sectional view of a portion of an engine cylinder and the inlet tube illustrating my invention.

Fig. II is a vertical section through the inlet tube and control magnet taken on the line II-II of Fig. I and

Fig. III is a circuit diagram.

In the drawings, the same reference numerals refer to similar parts throughout the several views, and the sectional views are taken looking in the direction of the arrows at the ends of the section lines.

Referring to the drawing, an internal combustion engine 5 of the air-cooled sleeve-valve type, is shown having an inlet passage 6 to which is attached one end of intake tube 7, the exhaust passage being located on another side of the engine (not shown). The intake tube 7 is provided at the opposite end with a chamber 9 closed by a cap 10 and communicating with a downwardly extending passage 11, through which the engine draws its air supply. Intermediate its ends the intake tube 7 is formed with a Venturi tube 12 at whose neck portion the fuel enters. The outer conical portion of the Venturi tube is shown provided with a conical sleeve member 13 which has an annular channel 14 communicating with the intake passage 15 and with the Venturi tube 12 through a number of small openings 16.

Fuel enters through a nozzle 17 screwed into the tube 7 and covered by a plug 18. A suitable fuel pipe, not shown, leading from the fuel reservoir connects at 19 to convey fuel to the nozzle.

Seated upon the top of the intake tube 7 is the electro-magnetic valve mechanism 20. This mechanism is supported and housed by a casing 21 and a plate 22 secured by screws 23 to the intake tube 7. Attached to the casing 21 and plate 22 is a guide tube 24 which on its exterior supports a series coil 25, suitably insulated therefrom, and loosely fitting within it is a movable core member 26 having an extension 27 of smaller diameter which slides in a suitable opening in the top of the intake tube 7. The tube 24, it will be noticed, extends down into an opening in the intake tube 7 for a short dis-

tance and the shoulder between that opening and the opening for the extension 27 provides a stop to limit the downward movement of the core 26. Secured to the top of the casing 21, as by a threaded engagement, is a fixed core member 30 having a small ring 31 of non-magnetic material embedded therein and projecting a short distance below it for the purpose of preventing contact between the stationary and movable core members. In order to adjust the weight of the movable core member 26, it is provided with a tube 33 secured thereto by a pin 34 and closed at its upper end by a cap 35 which tube is partially filled with shot 36. By putting in or taking out shot the magnet can be adjusted to operate at any desired excitation. A conduit 37 carrying wires 48 is shown connected to the lower portion of the magnet casing.

According to the circuit diagram of Fig. III, the internal combustion engine 5 is shown directly connected with a generator 40 electrically connected through a relay 41 to a storage battery 42, an ampere hour meter 43 and a load circuit 44 to which translating devices, such as a lamp 45 and a motor 46 may be connected. In series with the load circuit 44 are the wires 48 extending up to the electro-magnetic valve device 20 whereby this device is adapted to respond to the load current.

In the operation of the device, assuming the engine to be running and the generator delivering current to the battery or load or both and assuming further that the load current is below a predetermined value, as for example 15 amperes, the movable core member 26 will be in its lowermost or released position and the extension 27 will restrict the free flow of air and fuel to the engine. Under these conditions the excitation of the series coil 25 will be insufficient to lift the movable core member 26 against the force of gravity. However, should additional translating devices be thrown on the load circuit and the total load current thereby increased above a predetermined value, say 15 amperes, then the excitation of the series coil will be sufficient to lift the core 26 until it contacts with the spacing ring 31 and thereby raise the extension 27 to such a position that the opening through the Venturi tube is substantially unrestricted. In this position additional air and fuel are taken by the engine and the speed thereby increases an amount such that the generator is able to carry the load entirely and also charge the battery, the amount of charge, of course, depending upon the load or it may merely assist the battery in carrying the load. When the load is re-

duced to a value, slightly below the value at which the valve is lifted the core member 26 is released and the extension 27 again resumes its former position, restricting the free flow of air and fuel to the engine. It is to be noted that while the output of the generator at the higher engine speed would occasion a dangerously high charging rate for the battery should all or nearly all of it be consumed by the battery, with this device under no circumstances can the battery be charged at an excessive rate, inasmuch as the engine is controlled by the current flow in the load circuit and its speed is automatically reduced as soon as the load current is reduced to a safe charging value.

Inasmuch as the invention herein disclosed is susceptible of various other embodiments and as various changes might be made in the embodiment set forth, it is to be understood that all matter described above or shown in the accompanying drawing is to be interpreted as illustrative only, and not in a limiting sense.

Having thus described my invention, what I claim as new and desire to secure by Letters Patent, is:

1. The combination of an internal combustion engine, a member having a Venturi tube therein for conveying air and fuel to said engine, a casing mounted on said member, a coil in said casing, a plunger core adapted to slide in said coil, means for varying the weight of said core, a stationary core member in said coil toward which said pliable core is lifted, said first member having an opening in alignment with said plunger core and the neck of said Venturi tube and said plunger core having a portion extending down through said opening into said tube whereby the passage of air and fuel is normally restricted but is permitted to pass freely when the coil is energized sufficiently to lift the plunger core.

2. An engine regulating mechanism for internal combustion engines, having an intake conduit for fuel gases and a valve in said conduit; electro-magnetic means for moving the valve comprising a support; a stationary coil positioned on the support; a movable core in operative relationship with the coil and adapted to be moved thereby when said coil is electrically energized; and a well within the movable core adapted to receive a plurality of weighted particles whereby the point of initial movement of said core and attached valve may be varied, the upper end of said well extending above the top of said coil whereby the interior of said well is always accessible.

In testimony whereof, I affix my signature.
SAMUEL WILBUR.
